UNITED STATES PATENT OFFICE

160,093

COMBINED NAIL LACQUER BOTTLE AND APPLICATOR

Irvin R. Linnard, Montclair, N. J.

Application June 9, 1949, Serial No. 3,167

Term of patent 14 years

(Cl. D58—8)

To all whom it may concern:

Be it known that I, Irvin R. Linnard, a citizen of the United States of America, residing at Montclair, in the county of Essex, State of New Jersey, have invented a new, original, and ornamental Design for a Combined Nail Lacquer Bottle and Applicator, of which the following is a specification, reference being had to the accompanying drawing, forming part thereof.

Fig. 1 is a side elevational view of a combined nail lacquer bottle and applicator, showing my new design.

Fig. 2 is an end elevational view, and

Fig. 3 is a top plan view thereof.

I claim:

The ornamental design for a combined nail lacquer bottle and applicator, as shown.

IRVIN R. LINNARD.
